CLAIM

We claim the ornamental design for a light sensor, as shown and described.

DESCRIPTION

FIG. 1 is a rear elevation view of a light sensor of the present disclosure;

FIG. 2 is a right side elevation view thereof;

FIG. 3 is an enlarged detail view of area 3 shown in FIG. 1; and,

FIG. 4 is an enlarged detail view of area 4 shown in FIG. 2. The even broken lines illustrate portions that form no part of the claimed design.

The dash-dot-dash broken lines represent the boundaries and indicators of the enlarged detail views. The broken lines form no part of the claimed design.

1 Claim, 4 Drawing Sheets
